UNITED STATES PATENT OFFICE.

WILLIAM SYLVESTER PENN, OF ATLANTA, GEORGIA.

UMBRELLA-FRAME.

1,136,887.

Specification of Letters Patent. Patented Apr. 20, 1915.

Application filed June 3, 1914. Serial No. 842,731.

To all whom it may concern:

Be it known that I, WILLIAM SYLVESTER PENN, a citizen of the United States, residing at Atlanta, in the county of Fulton and State of Georgia, have invented certain new and useful Improvements in Umbrella-Frames, of which the following is a specification, reference being had to the accompanying drawings.

10 This invention relates to new and useful improvements in umbrellas, and particularly to umbrella frames which include removable stretchers.

An object of this invention is the provision 15 of an umbrella frame including stretchers which are formed with identical ends, the ends being readily detachable from the runner on the staff and the ribs of the umbrella, so that the stretchers are interchangeable, any one of the stretchers being adapted 20 for disconnection from the frame individually without disturbing the adjacent stretchers.

Another object of this invention is the 25 provision of an umbrella frame which includes a staff upon which a runner is slidably mounted, the runner being adapted to receive the inner ends of the stretchers therein, and the runner supporting an inner 30 protecting sleeve which engages the periphery of the staff, the inner ends of the stretchers engaging against the sleeve to be held thereby against bearing frictionally against the staff as the stretchers are opened 35 or closed.

With these and other objects in view, my invention consists in the novel construction, combination and arrangement of parts to be hereinafter more fully described, claimed 40 and illustrated in the accompanying drawing in which,

Figure 1 is an elevational view, partly in section, of my improved umbrella frame; Fig. 2 is a sectional view on the line 2—2 45 of Fig. 1; Fig. 3 is a fragmentary perspective view, showing one end of one of the stretchers; Fig. 4 is an end view of the thimble mounted on the shaft; Fig. 5 is a fragmentary elevational view showing the alter-

native form of bracket connected to the 50 ribs; and Fig. 6 is a sectional view on the line 6—6 of Fig. 5; Fig. 7 is a detail plan view of the blank on which the geat or bracket is made.

Referring more particularly to the drawing, the numeral 1 designates the staff of my improved umbrella frame, and secured to the staff, adjacent its outer end, is a thimble 2, and slidably mounted upon the staff, inwardly of the thimble, is a runner 3. The 55 thimble 2 and the runner 3 are identical in construction, and they are each bulged outwardly intermediate of their ends as at 4, the bulged portion of the members being provided with longitudinally extending 60 elongated slots 5. The runner 3 is slightly 65 larger in diameter than the thimble, and within the runner, a sleeve 6 is mounted, the opposite ends of the sleeve being turned outwardly to engage the opposite ends of the 70 runner, whereby the sleeve is held in position within the runner. Pivotedly mounted within the bulged portion of the thimble 2, are the inner T-heads 7 of the ribs 8, the heads 7 being of a length slightly shorter 75 than the length of the slots 5 in the thimble so that the heads may be readily inserted into the bulged portion of the thimble and turned to extend across the slots so that the 80 same are held within the thimble against accidental displacement. Similarly mounted within the bulged portion 4 of the runner are the inner T-heads 9 of the stretchers 10, the outer ends of the stretchers being 85 also formed with T-heads 11 which are pivotedly connected to the ribs 8 intermediate of their ends within brackets.

Each of the brackets or geats is formed from a strip of metal 12 which is provided at its opposite ends with transversely extending 90 heads 13, the body portion of each plate being provided with an elongated slot 14 as illustrated in Fig. 7. The transverse heads 13 of each bracket are disposed around one of the ribs 8, and secured thereto by pins 95 or other suitable fastening devices, the slotted portion of the bracket being bowed inwardly to provide a seat between the rib

and the bowed portion of the bracket to receive the T-head 11 on the outer end of one of the stretchers therein.

In the practical use of my improved device, 5 the various parts of the frame are attached in the following manner:—The thimble 2 is secured to the staff, adjacent its outer end, by rivets or other suitable fastening devices and the runner 3 having the sleeve 6 mounted therein is slidably disposed upon the staff inwardly of the thimble. The ribs 8 are then disposed so that the T-heads 7 on the inner ends thereof, are arranged to extend longitudinally of the slots 5 in the thimble 15 so that the heads may be readily inserted into the thimble and turned to extend across the slots, whereupon the stretchers 10 are disposed with the heads 9 on their inner ends within the slots in the bulged portion 20 4. The ribs 8 are then moved inwardly to force the T-heads 11 on the outer ends of the stretchers through the slotted portions of the brackets, the geats on the ribs. When the parts are in this position, the stretcher 25 may be turned to dispose its heads across the slot 5 in the runner and the slot 14 in the bracket so that the several parts are connected in operative position.

From the above description, taken in connection with the accompanying drawing, it 30 will be seen that I have provided an umbrella frame in which any one of the stretchers or ribs may be removed without disturbing the adjacent stretchers or ribs, and by providing the sleeve 6 within the runner 3, undue wear upon the staff which is usually imposed thereupon by the engagement of the heads upon the inner ends of the stretchers therewith, is prevented.

40 In Figs. 5 and 6 of the drawing, I have illustrated an alternative form of bracket for pivotally connecting the T-heads 11' on the outer ends of the stretchers 10' to the ribs 8', each of the brackets consisting of 45 an elongated flexible plate 15 which is provided with apertures 16 in its opposite ends, the plates being adapted to engage around the ribs and being secured thereto by pins 17, the free apertured ends of the plates 50 being disposed in spaced relation to receive the opposite ends of the T-heads 11'. As the plates are flexible, the apertured ends thereof bend inwardly or outwardly when it is desired to connect or disconnect the 55 stretchers and the ribs.

Having thus fully described my invention, what I desire to claim and secure by Letters Patent, is:—

1. An umbrella frame comprising a staff, 60 a thimble connected to the staff adjacent its outer end, a runner slidably mounted upon the staff inwardly of the thimble, ribs pivotally connected to the thimble, stretchers pivotally connected at their inner ends to 65 the runner, a bracket connected to each of

the ribs intermediate of its ends, each of the brackets comprising a strip having an inwardly bowed slotted portion, and the outer end of each of the stretchers being provided with a T-shaped head for engagement through the slot of the corresponding bracket, the length of the slot being longer than the length of the T-shaped head, whereby the stretchers may be turned to pivotally connect the same to the brackets. 70 75

2. An umbrella frame comprising a staff, a thimble connected to the staff adjacent its outer ends, a runner slidably mounted upon the staff inwardly of the thimble, ribs pivotally connected to the thimble, stretchers 80 pivotally connected at their inner ends in said runner, a bracket connected to each of the ribs intermediate of its ends, each of said brackets comprising an elongated strip having transversely extending heads at its 85 ends, the heads of each bracket being secured around one of the ribs, the body portion of each strip being slotted and being bowed inwardly to provide a seat between the rib and the bowed portion of the plate, 90 and the end of each of said stretchers being provided with a T-head whereby the same may be extended through the slot of one of the brackets and turned to extend across the slot, whereby the stretchers are pivotally 95 connected to the ribs.

3. In an umbrella, a staff, a runner mounted upon the staff, a rib mounted upon the staff, a geat or bracket mounted upon the rib, the runner being provided with an outwardly 100 bowed and longitudinally slotted portion, the geat being formed with outwardly projecting oppositely disposed spaced eyes, and a stretcher having at each end an identical cross bar, said cross bar and the adjacent 105 portion of the stretcher being less in thickness than the slot in the runner or the space between the eyes on the geat, whereby to permit the insertion of the cross bars respectively into the geat and runner, the rotation 110 of the stretcher bringing said cross bar into position at right angles to the space in the geat between the eyes and the slot in said runner, thus pivotally and detachably connecting the stretcher with the runner and 115 the rib.

4. In an umbrella, a staff, a runner on the staff, a rib pivoted at its inner end to the staff, said rib being U-shaped in cross section, the open face of the rib being disposed toward the staff, the runner being formed with an outwardly bowed portion longitudinally slotted, a geat or bracket mounted upon the rib and having an inwardly bowed longitudinally slotted portion disposed in 125 line with the hollow of the rib, and a stretcher having at opposite extremities thereof identical cross bars, the cross bars and the adjacent portions of the stretcher having a width less than the width of said 130

slots and a length greater than the width of the slots whereby the cross bars may be inserted in said slots in the geat and runner and the stretcher rotated to turn the cross bars at right angles to the slots, thereby pivotally connecting the stretcher with the runner and geat, respectively.

In testimony whereof I hereunto affix my signature in the presence of two witnesses.

WILLIAM SYLVESTER PENN.
